UNITED STATES PATENT OFFICE.

CHARLES F. SHUMAKER, OF SILVER CREEK, NEW YORK.

GRAIN-CLEANING MACHINE.

SPECIFICATION forming part of Letters Patent No. 273,174, dated February 27, 1883.

Application filed October 9, 1882. (No model.)

To all whom it may concern:

Be it known that I, CHARLES F. SHUMAKER, of Silver Creek, in the county of Chautauqua and State of New York, have invented new and useful Improvements in Grain-Cleaning Machines, of which the following is a specification.

This invention relates to an improvement in that class of machines which are employed for removing the impurities from the kernels of grain previous to grinding the same into flour or otherwise reducing the same, and which are provided with brushes operating upon the kernels of grain.

It has been heretofore proposed to pass the grain between a pair of reciprocating brushes for freeing the grain from the adhering foreign matter; but this construction is not effectual because the brushes do not hold the grain sufficiently and do not form a bed possessing sufficient rigidity to permit the effectual scouring of the grain. It has also been proposed to employ an endless scouring-apron in connection with a stationary brush; but this construction is not effectual, because the traveling scouring-surface, in passing over the brush at all times in the same direction, bends the tufts of the brush in the direction in which the scouring-surface moves, and the kernels of grain will lie comparatively still in the grooves of the traveling scouring-surface and be subjected only to a wiping action as they pass over the brush.

The object of my invention is to so construct the machine that the kernels will be subjected to a severe scouring and brushing action on all sides without danger of being broken; and my invention consists, to that end, of the improved construction, as will be hereinafter fully described, and pointed out in the claims.

In the accompanying drawings, consisting of two sheets, Figure 1 represents a vertical longitudinal section of my improved grain-cleaning machine. Fig. 2 is a vertical section in line xx , Fig. 1. Fig. 3 is a horizontal cross-section of the machine. Fig. 4 represents some of the metallic rubbing-plates in vertical section on an enlarged scale, and Fig. 5 is a fragmentary rear elevation of said plates.

Like letters of reference refer to like parts in the several figures.

A represents the stationary frame of the machine, and A' the inclosing-casing secured thereto.

b is the driving-shaft supported in bearings b', secured to the top of the frame A, and provided with a pulley, B, or some other suitable device whereby the shaft is rotated.

C represents a reciprocating brush, arranged within the casing A', below the shaft b, and actuated from the latter by means of eccentrics c, formed on the shaft b, and rods c', connecting the eccentrics c with the stock d of the brush C, so that the rotating movement of the shaft b produces a reciprocating motion of the brush. The stock d of the brush is guided on both sides in vertical ways E, which are made horizontally adjustable by horizontal screws e, arranged near the upper and lower ends of the ways E, the latter being guided in horizontal ways f f, attached to the inclosing-casing A'. 70

G represents an endless apron, arranged to run in contact on one side with the brush C, and composed preferably of a series of metallic plates suitably articulated or connected together by flexible connections, which permit the apron to run around the pulleys or drums H H', arranged one above the other in the casing A' in front of the brush C. As represented in Figs. 2 and 3, the several plates g, composing the endless apron G, extend across the entire width of the brush C, and are connected together by hinges i, arranged at the inner sides of the plates, Figs. 4 and 5. If preferred, however, the plates may be riveted or otherwise secured to an endless apron of canvas, leather, or other suitable material. The outer or face sides of the plates g are constructed with fine corrugations or ribs, as represented at j, to produce an abrading effect upon the kernels of grain which pass over the plates. 90 The shaft of the upper drum, H, extends through the side of the inclosing-casing A', and is provided with a pulley, k, which receives motion from the driving-shaft b by means of an endless belt, k', and pulley k'', the movement being such that the side of the endless apron which is adjacent to the brush moves in a downward direction. The descending side of the endless apron is preferably guided and supported against the pressure of the 100

brush by ribs or bars *l*, secured to the inner side of the casing *A'* and projecting behind the descending side of the endless apron.

5 *M* represents the feed-hopper, arranged above the inclosing-casing *A'*, and provided in its throat with a feed-roller, *m*, and feed-slide *m'*, of well-known construction.

10 *m²* represents a spout, which conducts the grain from the feed-hopper between the brush and the endless apron.

15 *n* represents the inclined bottom of the inclosing-casing *A'*, and *N* represents an ascending air-trunk, which receives the grain from the inclined bottom *n* through an opening, *n'*, and in which the dust and other light impurities which have been detached from the kernels of grain are separated from the grain, the latter passing downward and escaping from the lower end of the air-trunk *N*, while the dust 20 and light impurities are carried up by an air-current into the eye of a suction-fan, *O*, which discharges the dust out of doors or into a suitable dust-room.

25 The grain to be cleaned is fed by the spout *m²* between the faces of the reciprocating brush *C* and the descending side of the endless apron *G*, and is caused to pass downward between these two faces by the force of gravity and the downward motion of that side of the endless 30 apron. During the downward passage the grain is severely rubbed by the brush and the corrugated plate *G*, and the dust and other light impurities which adhere to the kernels of grain are thereby completely detached therefrom.

35 The operation of rubbing and brushing the grain is of considerable duration and very thorough, without, however, subjecting the grain to blows or shocks, which would tend to 40 break the kernels, and the grain is delivered from the machine unbroken and thoroughly

cleaned. The degree of pressure which the brush exerts on the kernels of grain may be increased or reduced at desire by adjusting the brush toward or from the endless apron by 45 means of the horizontal screws *e*. The brush and that portion of the endless apron against which the brush operates are preferably arranged vertically, as shown in the drawings; but, if desired, they may be arranged in an 50 inclined position.

I claim as my invention—

1. In a machine for cleaning grain, the combination of an endless apron provided with suitable rubbing-surfaces, a brush operating 55 against the rubbing-surfaces of the endless apron, mechanism whereby the endless apron is actuated, and mechanism whereby a reciprocating movement is imparted to the brush, substantially as set forth.

2. In a grain-cleaning machine, the combination of a reciprocating brush, an endless apron provided with suitable rubbing-surfaces, and means whereby the brush can be adjusted toward and from the endless apron, substantially as set forth.

3. The combination, with a reciprocating brush, *C*, and ways or guides in which the brush moves, of the traveling endless apron *G*, having grooved or ribbed plates *g*, substantially 70 as set forth.

4. The combination, with the endless apron *G*, provided with suitable rubbing-faces, of the reciprocating brush *C*, vertical ways *E*, in which the brush moves, horizontal guides *f*, and horizontally-adjustable screws *e*, substantially as set forth.
